UNITED STATES PATENT OFFICE.

ALBERT MOSHEIM, OF EAST ORANGE, NEW JERSEY.

VANITY CASE.

Application filed January 13, 1923. Serial No. 612,416.

To all whom it may concern:

Be it known that I, ALBERT MOSHEIM, a citizen of the United States, and a resident of East Orange, in the county of Essex and State of New Jersey, have invented new and useful Improvements in Vanity Cases, of which the following is a full, clear, and exact description.

This invention relates to vanity cases.

10 The general object of this invention is the provision of a simple, compact and attractive vanity case having a compartment for a powder cake, a compartment for rouge, and a space in which a lip stick may be placed, said compartments being adapted for containing the necessary means for applying the articles contained in them.

20 A further object of the invention is the provision of a vanity case, the compartments of which are so separated that there is no danger of the contents of one compartment being spilled into another compartment, and which is so constructed that one compartment may be closed while the other compartment is in use.

25 These objects are accomplished by providing a casing including a main body portion to which a lid carrying a mirror is hinged, and mounting in the body portion a frame for supporting a powder cake in the upper part of the body portion, slidably mounting in the bottom of the body portion a drawer that may be operated when the lid is closed and which is held in 30 any desired position by depending members carried by the frame, mounting in the drawer a rim for holding rouge and a powder puff, and forming from the bottom of the drawer upturned members for holding 35 a lip stick.

40 These and other objects of the invention will be more clearly understood from the following detailed description and accompanying drawings.

45 Figure 1 is a top plan view of the vanity case opened;

Figure 2 is a vertical section along the line 2—2, Figure 1, showing the construction of the vanity case;

50 Figure 3 is a vertical section along the line 3—3, Figure 2;

Figure 4 is a horizontal section along the line 4—4, Figure 3, showing a top plan view of the drawer;

55 Figure 5 is a perspective view of the

frame mounted in the casing for supporting the powder cake.

Referring to the above-mentioned drawings, the invention includes a casing 10 including a main body portion 11 to which a lid 12 is hinged at 13. Mounted in the lid 12 is a mirror 14 for the convenience of the user in applying the articles contained in the vanity case. A frame 15, including a rim 16 carrying a circular plate 17, two portions of which are doubled together and bent downward at right angles to the plate 17, forming depending members 18 and 19, is mounted in the main body portion 11. A powder cake 20 mounted on a plate 22 is located in the rim 16 and supported on the plate 17. Positioned on the powder cake and contained within the rim 16 is a powder puff 21 for applying the powder.

An opening 23, approximately equal in width to the distance between the depending members 18 and 19, is cut in the wall of the body portion 11. A drawer 24, shaped to fit into the opening 23, is slidably mounted in the bottom of the body portion 11, sliding between the depending members 18 and 19 which frictionally engage it so as to retain it in any desired position. Cut in the bottom of the body portion 11 is a slot 25 which extends parallel to the depending members 18 and 19. A guide 26 attached to the drawer 24 slides in the slot 25 and serves to limit the movement of the drawer. An annular member 33, in the form of a rim, is mounted in the drawer 24 forming a compartment for rouge and for the puff 29 for applying the rouge. Inturned lips 27 and 28 are formed integral with the rim for engaging the powder puff 29 to retain it in position in the annular member 33 and to hold it low enough in the drawer to prevent it from engaging the main body portion, thus restricting the free movement of the drawer. Two prongs 31 and 32 are projected upward from the bottom of the drawer 24. These prongs are spaced from the annular member 33 a sufficient distance to allow the placing of a lip stick 30 between them and the annular member.

In the operation of this vanity case, the drawer 24 may be projected outward by gripping the head of the guide 26 and moving it along the slot 25. The depending members 18 and 19 frictionally engage the sides of the drawer and serve to retain it

in any desired position. The drawer may be opened without opening the lid 12, thus the user may apply the rouge without any danger of spilling it into the compartment 5 containing the powder cake 20. Normally, in using this vanity case, the lid would be opened to present the mirror to the user and then the rouge and powder might be applied as desired.

10 I would state in conclusion that while the illustrated example constitutes a practical embodiment of my invention I do not limit myself strictly to the exact details herein illustrated since manifestly the same can 15 be considerably varied without departing from the spirit of the invention as defined in the appended claims.

Claims:

1. A vanity case, comprising a casing, a 20 frame mounted in the casing for supporting a powder cake, a drawer slidably mounted in the casing, members carried by the powder cake supporting frame frictionally engaging the drawer to retain it in any desired position, means mounted in the drawer for holding a powder puff, and means carried by the drawer for co-operating with the means provided for carrying the powder puff to hold the lip stick.

30 2. In a vanity case including a main body portion having a slot cut in its bottom, a drawer slidably mounted in said body portion, a guide slidably mounted in the slot in the bottom of the body portion and attached to the drawer to limit its movement, and means mounted in the body for retaining the drawer in any desired position.

35 3. In a vanity case including a main body portion having a slot cut in its bottom, a drawer slidably mounted in the body portion, a guide slidably mounted in the slot in the bottom of the body portion and attached to said drawer to limit its movement, means mounted in the body portion and co-operating with the drawer to retain the latter in any desired position, and means mounted in the drawer for holding a powder puff.

40 4. In a vanity case of the character described including a main body portion, a drawer slidably mounted in the bottom of the body portion, means for limiting the movement of said drawer, and a frame having depending members for frictionally engaging said drawer, said depending members serving to retain the drawer in any desired position.

45 5. In a vanity case of the character described including a main body portion, a drawer slidably mounted in said body portion, means mounted in the body portion for retaining the drawer in any desired position, and a rim carried by the drawer for holding a powder puff, said rim having in-turned lips for engaging the powder puff.

6. In a vanity case of the character described including a main body portion, a drawer slidably mounted in the body portion, means for limiting the movement of said drawer associated with the main body portion, means mounted in the main body portion for retaining the drawer in any desired position, a rim mounted in the drawer for containing a powder puff, lips formed on said rim for engaging the powder puff 75 to retain it in position, and upturned prongs formed in the bottom of the drawer for retaining a lip stick in position in the drawer.

7. A vanity case of the character described, comprising a main body portion, a lid carrying a mirror hinged to said body portion, a drawer slidably mounted in the body portion, a frame mounted in the body portion, and depending members carried by said frame for frictionally engaging the drawer to retain it in any desired position, said frame being shaped for holding a powder cake.

8. A vanity case of the character described, comprising a main body portion, a lid carrying a mirror hinged to said body portion, a drawer slidably mounted in the body portion, a frame for carrying a powder cake mounted in said body portion, depending members carried by said frame for frictionally engaging the drawer to retain it in any desired position, and a guide fixed to said drawer and slidably mounted in a slot cut in the bottom of the body portion for limiting the movement of the drawer.

9. In a vanity case including a main body portion, a frame mounted in said body portion, a drawer slidably mounted in the body portion, and means carried by said frame for frictionally engaging the drawer to retain it in any desired position.

10. A vanity case comprising a box member having a hinged top, a frame mounted in said box for supporting a powder cake in the top of the box, a drawer slidably mounted in the bottom of the box, depending members carried by said frame frictionally engaging the drawer to retain it in any desired position, means carried by the drawer and engaging the box for limiting the outward movement of the drawer, and means provided in said drawer for carrying a powder puff and a lip stick.

11. A vanity box comprising a main shell formed with a base and surrounding side-wall, said side-wall being provided with a drawer-receiving opening, a lid or cover connected with said side-wall, a drawer-guiding frame-member mounted upon said base, drawer-guides connected with said frame-member, and a drawer movably disposed between said guides.

12. A vanity box comprising a main shell formed with a base and surrounding side-wall, said side-wall being provided with a

drawer-receiving opening, a lid or cover connected with said side wall, a drawer guiding frame member mounted upon said base, drawer guides connected with said frame member, and a drawer movably disposed between said guides, a partition being disposed within said main shell at a point above the drawer so as to provide an auxiliary receiving chamber.

5

10 13. In a vanity box, a main receptacle, a

cover hingedly secured thereto for closing the same, a drawer guiding frame mounted in the main receptacle, a drawer slidably mounted in said drawer guiding frame and movable through an opening formed in the 15 side wall of the main receptacle, and a partition associated with the drawer guiding frame and dividing the main receptacle into two compartments.

ALBERT MOSHEIM.
